Primary Examiner — Eric Goodman*Assistant Examiner* — Steven Czyz*(74) Attorney, Agent, or Firm* — Workman Nydegger**(57) CLAIM**

The ornamental design for a fluid connector, as shown and described.

DESCRIPTION

FIG. 1 is a perspective view of a fluid connector showing my new design;

FIG. 2 is a right side elevational view thereof;

FIG. 3 is a left side elevational view thereof;

FIG. 4 is a front elevational view thereof;

FIG. 5 is a top plan view thereof;

FIG. 6 is a bottom plan view thereof; and,

FIG. 7 is a perspective view thereof with the three collars of the fluid connector rotated to a second position.

The broken lines are included for the purpose of illustrating portions of the article and form no part of the claimed design.

1 Claim, 4 Drawing Sheets(56)
